UNITED STATES PATENT OFFICE.

ABRAHAM ZILBERSHER, OF NEW YORK, N. Y.

SNOW CLEANER AND DIGGER.

Application filed May 5, 1926. Serial No. 106,970.

This invention relates to an improved snow shovel and digger, and has for an object to provide a construction which may be used for shoveling snow or used in digging earth, the arrangement being such that the snow or earth is lifted and discharged into a waiting conveyance.

Another object of the invention is to provide an apparatus which will dig into a bank through the power of the engine driving the apparatus and then lift the digging member for causing a part of the material to be discharged at a given point.

Another object of the invention is to provide a shovel and digger wherein the shovel may be adjusted longitudinally without preventing its swinging movement as it moves from a digging position to a discharge position.

A still further object of the invention is to provide an apparatus which may be used to shovel snow or dig earth or other material, the arrangement being such that the parts may be readily converted so as to be used in either way, and additionally converted to present a torch structure for melting snow or ice.

In the accompanying drawing—

Figure 1 is a longitudinal vertical sectional view through a snow shovel and digger disclosing an embodiment of the invention.

Figure 2 is a sectional view through Figure 1 on line 2—2.

Figure 3 is a sectional view through Figure 1 on line 3—3.

Figure 4 is a side view partly in section showing the driving means disclosed in Figure 1, the same being on an enlarged scale.

Figure 5 is a view similar to Figure 1 but showing only the front part of the structure with the shovel elevated, this figure including an attachment presenting a modified form of discharge.

Figure 6 is a detail fragmentary end view of the shovel shown in Figure 5 illustrating how the discharge material is deflected.

Figure 7 is a sectional view through Figure 5 substantially on line 7—7.

Figure 8 is a detail fragmentary view showing the front part of the shovel illustrated in Figure 1, and in connection therewith a torch or burner disclosing a modified form of the invention.

Figure 9 is a view similar to Figure 8 but showing a further modified structure where-

in the shovel is fitted with means for digging the earth.

Figure 10 is a top plan view of the digging head shown in Figure 9.

Figure 11 is a perspective view of one of the digging teeth and earth loosening members.

Figure 12 is a bottom plan view of one of the earth stirring blades.

Figure 13 is a fragmentary rear view of the cutting roller shown in Figure 1, the same disclosing certain features of the invention.

In constructing an apparatus disclosing the invention, it is aimed, among other things, to provide a strong and very simple structure wherein the parts may be adjusted for causing the shovel to take up snow, elevate the same a certain distance and discharge the snow into a wagon at one side of the apparatus. In addition, it is aimed to provide means which may be associated with the shovel, whereby the shovel may readily remove earth and discharge the same in the same manner as it discharges snow. In addition to these two features, an additional attachment may be provided and associated with the shovel, whereby snow or ice may be melted and allowed to run away as water instead of bodily removed.

The accompanying drawings show a construction for accomplishing these different results, wherein 1 indicates a frame of any desired kind formed with suitable platforms, braces and the like and supported by suitable traction wheels 2. The front traction wheels 2 are driven by suitable mechanism through the shaft 3. The shaft 3 is provided with a clutch member 4 co-acting with a clutch member 5 splined on the shaft 6 which is rotated by the engine 7. The engine 7 may be of any desired kind, as, for instance, an ordinary internal combustion engine. The engine 7 is supplied with the usual reversing mechanism 8, whereby shaft 6 may be driven in either direction. A gear wheel 9 is loosely mounted on shaft 6 and carries a clutch member 10 co-acting with clutch 5 so that when the clutch 5 is interlocked with the clutch member 10, sprocket wheel 9 will rotate and will drive the sprocket chain 11, which in turn will drive the sprocket wheel 12. The sprocket wheel 12 is rigidly secured to a shaft 13 carrying a pinion 14 continually meshing with the bevel gear 15. Gear 15 is rigidly secured to a drum 16,

which drum is adapted to wind the rope or cable 17. A brake drum 18 is rigidly connected with the drum 16 and co-acts with the brake band 19 connected with the foot pedal 20, whereby if the pedal 20 is pressed downwardly, the brake band will produce a braking action on the brake drum 18 and thereby stop the rotation of the drum 16 or rigidly hold the drum in a given position. The clutch member 5 is connected through suitable levers, links and the like to a hand controlled lever 21, whereby the clutch member 5 may be moved into engagement with clutch 4 or clutch 10 so as to 15 rotate the drum 16 or shaft 3 as preferred.

Cable 17 extends over a pulley 22 carried by part of the frame 1. From pulley 22 cable 17 extends downwardly and is connected at 23 to a shovel guide 24, said shovel 20 guide being preferably rectangular and pivotally mounted at 25 on part of the frame 1. The shovel 26 is provided with a rectangular section 27 and an excavating section 28. Section 25 27 is provided with spaced projections or enlargements 29, between any of which a set screw 30 may be forced for locking the shovel 26 in different adjusted positions in respect to the guide 24. A rest or brace 31 is secured in any desired manner to the frame 1 and acts to prevent the rearward swinging movement of the shovel 26 beyond a certain point and also permits pressure to be brought on the shovel to force the shovel into snow, earth or some other substance. In case it should be desired to have the excavating section 28 operate at a higher point than that shown in Figure 1, the screw member 32 is moved in the proper direction for causing the abutment 33 to gradually 35 swing the shovel upwardly. When the device is in operation, the engine 7 is, of course, operating and the control lever 21 is shifted to cause clutch 5 to engage clutch 4. This will cause the rotation of the traction wheels 40 and move the apparatus until the excavating section 28 has excavated or been inserted into a supply of snow or other material 34. When the right amount of snow has been secured, lever 21 is shifted so that 45 clutch 5 will be disengaged from clutch 4 and will be moved almost immediately over into engagement with clutch 10. This will stop the forward movement of the apparatus and will immediately cause a rotation of drum 16 for winding cable 17. Upon the winding of cable 17, the guide 24 and the shovel 26 and associated parts will be immediately swung upwardly to, for instance, the position shown in Figure 5. As the shovel moves to substantially this position, the snow or other material will slide under the action of gravity downwardly and be discharged out the inner end of guide 24 so as to be received by the chute 35. This 55 chute, as shown in Figure 2, is provided

with a tilting blade 36 which acts as a shifting device or switch for causing the snow to be discharged out the auxiliary chutes 37 or 38. When the apparatus is in use, a wagon or receptacle of some kind is placed 60 under either of the chutes 37 or 38, and as the snow is discharged the wagon or other container will receive the same. In case it is desired to discharge the excavated material at a higher point, the same is caused 65 to pass out the auxiliary chutes 39 or 40. This is done by using the modified structure shown in Figures 5 and 6. This modified structure consists of an end member 41 adapted to be bolted to the guide 24, and a 70 deflecting member 42 which is removably positioned in the inner end of the guide 24. The deflecting member 42 is held in place by a hook and eye structure 43, and at one 75 end is supported by a bracket 44. When discharging out the other auxiliary chute, the plate 45 is shifted to the opposite side. The deflecting member 42 must, of course, be 80 manually placed in position and manually shifted from one angle to the other to determine which of the auxiliary chutes 85 39 or 40 is to be used. In respect to the deflecting member 36, however, the same is mounted on the pivotally mounted shaft 46 which carries a crank 47 at the outer part, the crank being held in either of its positions by a suitable pin 48. At the rear of the apparatus, there is provided a number 90 of cutting disks 49 rigidly secured to the shaft 50 which is rotatably mounted and which is carried by springs 51, which springs have one end connected with the frame 1 while the opposite end is normally supported by a cable 52 held in a given position by a drum 53. The drum 53 is locked in any desired position by any suitable means, as, for instance, a pawl and ratchet, and is rotated manually by a suitable crank 54. When it is desired to cut the 95 snow or ice or to cut the earth, the disks 49 are lowered to the dotted position shown in Figure 1 and the apparatus moved over the surface to cut. When the cutters are not in use, they are preferably held elevated, as 100 shown in Figure 1. To prevent snow, ice or other matter from clogging the cutting disks 49, suitable pins 55 are provided which 105 act as cleaning members.

When the apparatus is to excavate earth, 110 preferably an excavating head is provided, as shown in Figures 9 and 10, said head consisting of a number of excavating teeth 56 and a number of stirring blades 57. These are bolted or riveted in place at the forward end of the excavating section 28 of shovel 26. Where the ground needs to be loosened up, the apparatus is moved backwardly so that the blades 57 may be pulled through the earth and loosen the same. After this has been done, the apparatus is 115 120 125 130

again moved forwardly and the teeth 56 will further loosen up the earth and help guide the same onto the excavating section 28, from which it is moved by gravity in a 5 similar manner to the way the snow is caused to be moved. In order to prevent an upward swinging of the shovel 26 when the blades 57 are functioning, a hook 58 is used, said hook fitting over a pin 59. A cable 10 60 extends from hook 59 to an operator's position near engine 7, whereby the operator may at the proper time raise hook 58 so as to permit the shovel to be swung upwardly in substantially the position shown 15 in Figure 5.

Under some circumstances, it might be desired to melt the snow or ice, and when this is the case suitable bars 61 are connected by bolts or otherwise to the excavating section 28 of shovel 26. The bars 61 are adapted to receive the respective hooks 62 which are rigidly secured to a burner 63, said burner being supplied with gasoline or other combustible matter. This burner may 20 be of any desired kind but preferably one that will cover a comparatively large surface and one wherein the flames will be projected downwardly in order to secure the best melting action.

30 It will be noted that the burner may be used not only to melt snow and ice, but may be used to melt asphalt or other material, and in the case of melting of asphalt the device may be readily used to pick up by the 35 shovel the melted or properly burned asphalt and move the same to a truck for disposal.

Having thus described my invention, I claim:

40 1. In an apparatus of the character described, a shovel formed with a rectangular tubular body merging into an excavating

structure, a rectangular tubular guide for the shovel, said body being telescopically mounted in said guide, means for pivotally 45 mounting said guide at the inner end, means for locking said shovel to the guide, means permitting a longitudinal adjustment of the shovel in respect to the guide, means for swinging said guide so as to tilt the shovel 50 upwardly and allow the matter removed by the shovel to pass by gravity through the guide, and means for receiving said matter and discharging same at one side of the apparatus. 55

2. In an apparatus of the character described, a frame, a swinging shovel for excavating and discharging material into substantially the center of the frame, and a plurality of means co-acting with said 60 shovel for causing the matter to be discharged into the frame to be moved to one side of the same and discharged therefrom at different elevations.

3. In an apparatus of the character described, a frame, a swinging shovel for elevating material being excavated, a series of chutes arranged at different heights carried by the frame, and a plurality of means for causing the shovel to discharge through any 70 of said chutes.

4. In an apparatus of the character described, a frame, a pivotally mounted shovel carried by the frame adapted to excavate snow and other material, means for raising 75 said shovel so that the matter excavated thereby may be discharged out a given point, means carried by the frame for normally bracing the shovel when being forced into snow or other material, and a screw actuated 80 member carried by the frame for supporting the shovel at a point in advance and above the first mentioned bracing means.

ABRAHAM ZILBERSHER.
